UNITED STATES PATENT OFFICE.

HENRY W. BEESTON, OF PHILADELPHIA, PENNSYLVANIA.

DESIGN FOR AN UMBRELLA-STAND.

SPECIFICATION forming part of Design No. 19,429, dated November 19, 1889.

Application filed September 26, 1889. Serial No. 325,178. Term of patent 3½ years.

To all whom it may concern:

Be it known that I, HENRY W. BEESTON, a citizen of the United States, residing at Philadelphia, in the county of Philadelphia and State of Pennsylvania, have invented and produced a new and original Design for Umbrella-Stands, of which the following is a specification, reference being had to the accompanying drawing, forming part thereof.

My invention has relation to umbrella-stands or receptacles for holding umbrellas, canes, or the like, and has for its object the production of a new and original design which will present a highly ornamental and attractive appearance.

My invention consists in an umbrella-stand of cylindrical shape, with a suitable base or bottom and a top, the main portion or body of such stands between said top and bottom having or being provided with ribs or ridges radiating from a common point in the center of said body and extending to the edges thereof at equal distances apart, the spaces between said ridges enlarging in width as they lengthen and being slightly depressed or concaved, the effect being substantially a "sun-burst," and the appearance of the body,

when viewed in cross-section, being wave-like or undulatory.

In the drawings, D represents the body or main portion of the umbrella-stand; d, the radial ribs or ridges, and d' the concavities or depressions, said ribs radiating from the center of the length of the body D, as shown.

E represents the flaring top or dome, and F the flaring base or bottom with the round moldings f, said top and bottom being secured to the body D at e and f', respectively.

What I claim as new, and desire to secure by Letters Patent, is—

The design for umbrella-stands, consisting of the cylindrical body portion D, provided with a base and a top, and having the radial ridges d and the intermediate depressions or concavities d', substantially as shown and described.

In testimony that I claim the foregoing I have hereunto set my hand this 24th day of September, A. D. 1889.

HENRY W. BEESTON.
